UNITED STATES PATENT OFFICE.

RICHARD KEYTE, OF WHANGAREI, NEW ZEALAND, ASSIGNOR TO CHARLES ERNEST RANDOLPH MACKESY, OF THE HILL, WHANGAREI, AUCKLAND, NEW ZEALAND.

MEANS FOR AUTOMATICALLY INDICATING CHANGES IN TEMPERATURE.

SPECIFICATION forming part of Letters Patent No. 704,966, dated July 15, 1902.

Application filed May 20, 1902. Serial No. 108,290. (No model.)

To all whom it may concern:

Be it known that I, RICHARD KEYTE, a subject of the King of Great Britain, residing at Whangarei, Auckland, New Zealand, have invented a new and useful Means for Automatically Indicating a Change in Temperature; and I do hereby declare the following to be a full, clear, and exact description of the same.

This invention has been devised for the purpose of providing means whereby an alarm may be given upon a change of temperature occurring in the vicinity of the appliance. It is specially applicable for giving an alarm in case of a fire; but it may be used to indicate an abnormal fall in the temperature of the freezing-chambers of ships' holds, &c., or for any purpose in which it is desired an alarm should be given when the temperature rises or falls any specific amount.

The appliances employed consist of an ordinary mechanical spring-bell that is fastened upon a suitable base and which when wound up is prevented from ringing by means of a collar upon a spring-inclosed spindle engag-
ing with and holding the tongue of the bell. To the bottom extremity of this rod or spindle is attached a small capsule composed of two sheets of a flexible material whose edges are sealed together so as to inclose a space. Into this space is inserted ether or other gas that expands or contracts rapidly when exposed to heat or cold.

In the accompanying drawings, Figure 1 is a side elevation of the alarm, the bell being shown in section. Fig. 2 is a plan of the same.

a is the bell, that is screwed upon a central spindle *b*, attached to the frame *c*, and the tongue *d* of which is actuated by means of the escapement *e* engaging with the teeth of the escapement-wheel *f*. This escapement-wheel is caused to revolve by means of a suitable train of wheels actuated by the coiled spring *g*, that is wound around the spindle *b*. The spring *g* is placed in tension by turning the bell *a* so as to wind the spring up, when its tendency will be to cause the spindle and bell to revolve in the opposite direction, so as to actuate the tongue *d*.

Under normal conditions the tongue *d* is prevented from moving by means of the collar

h on the sliding spindle *j* pressing against it, such collar being kept in engagement with it by means of the spring *k*, surrounding the spindle, and the ends of which bear, respectively, against the collar and part of the frame *c*.

The base of the bell-frame *c* is secured in any approved manner to the supporting-frame *l*, that is formed with a flanged portion *m*, by means of which it may be attached to the ceiling of a room or in any position it is desired to place the alarm.

The end of the sliding spindle *j* projects outside the base of the bell-frame and its end is attached to the center of a capsule *n*, composed of two diaphragms of thin flexible metal, with their edges fastened together, so as to inclose a space. This space is filled with ether or any other suitable fluid that will expand or contract readily when subjected to slight rises or falls in temperature. A regulating-screw *o* passes through the supporting-frame *l* and its end bears against the free side of the capsule *n*.

Upon an abnormal rise in temperature occurring in the vicinity of the alarm the fluid contained in the capsule *n* will be caused to expand, thus bulging out the sides of the capsule. Owing to the screw *o* being a fixture, the full amount of the movement of the sides will be exerted upon the end of the sliding spindle *j*, which will thus be pushed in, freeing its collar *h* from contact with the bell-tongue, so that it will be free to act and sound an alarm, which will continue sounding until the temperature is lowered or the tension in the spring *g* becomes exhausted.

When it is desired to have the alarm to sound upon a fall in temperature taking place, the fluid will be placed in the capsule *n* in an expanded condition, so that when contracted by cold the two sides of the capsule will be drawn together. In this case the collar *h* and spring *k* would bear against the other side of the tongue to that shown in the drawings, so that when the spindle *j* is drawn out the collar will free the tongue.

By means of the screw *o* the amount that the capsule *n* will expand before releasing the bell-tongue may be regulated and also

the alarm set so as to sound upon any desired temperature being reached.

It is to be understood that I do not confine myself to the use of a mechanical bell such as that described herein and shown in the drawings, as such bell is shown for the purpose of illustrating the invention, and other descriptions and constructions of bells might be employed with equal effectiveness.

10 What I claim as my invention, and desire to secure by Letters Patent, is—

15 1. In means for indicating a change in temperature, a bell provided with a spring-actuated tongue, a collar upon a sliding spindle engaging with and holding the tongue from movement, and a capsule upon the end of the spindle composed of flexible walls and containing a fluid of a nature such that it will expand and contract when subjected to heat and cold, as herein specified.

20 2. In means for indicating a change in tem-

perature, a bell provided with a spring-actuated tongue and mounted upon a suitable base secured to a frame by means of which it may be fixed in any desired position, a collar upon a spring-sliding spindle engaging with and holding the tongue, a capsule composed of flexible walls and containing a fluid susceptible to expansion and contraction by heat and cold which is secured to the end of the sliding spindle, and a regulating-screw within the frame, the end of which bears against the other side of the capsule, as herein set forth.

25 In testimony whereof I have signed this specification in the presence of two subscribing witnesses.

RICHARD KEYTE.
